DESIGN FOR A CIGARETTE LIGHTER OR SIMILAR ARTICLE

Oscar Beffert, New York, N. Y., assignor to Guth-
Stern & Co., Inc., a corporation of New York

Application November 18, 1940, Serial No. 96,648

Term of patent 14 years

To all whom it may concern:

Be it known that Oscar Beffert, a national of the German Reich and resident of city of New York, in the county of Queens and State of New York, has invented a new, original, and ornamental Design for a Cigarette Lighter or Similar Article, of which the following is a specification, reference being had to the accompanying drawing, forming part thereof, in which, Figs. 1, 2 and 3 are front, side and bottom plan views, respectively, of a cigarette lighter, showing my new design in closed position, and Fig. 4 is a perspective view showing my new design of a cigarette lighter with the closure cap portion raised from its closed position.

I claim:

The ornamental design for a cigarette lighter or similar article, as shown.

OSCAR BEFFERT.
